UNITED STATES PATENT OFFICE.

NAHUM J. BUSBY, OF MAPLEWOOD, MASSACHUSETTS.

ALARM FOR DOORS, &c.

SPECIFICATION forming part of Letters Patent No. 399,242, dated March 12, 1889.

Application filed April 21, 1888. Serial No. 271,430. (No model.)

To all whom it may concern:

Be it known that I, NAHUM J. BUSBY, a citizen of the United States, residing at Maplewood, in the county of Middlesex and State of Massachusetts, have invented certain new and useful Improvements in Alarms for Doors, &c.; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is a front view of the bell-striking mechanism as it appears without the bell, and the front plate for supporting the arbors of the wheels and the posts of the frame-work of the alarm. Fig. 2 is a side view of the 20 frame and its mechanism, the bell being shown in section.

25 My present invention relates to improvements in that class of alarms for doors, &c., such as is represented and described in United States Patent No. 361,048, granted me on the 12th day of April, 1887.

In carrying out my present improvements I do away with the take-up spring K, (shown in said patent,) and in place thereof I provide 30 an arm, O, secured to the arbor w, pivoted in the disk i and in the back plate or bracket, F; also I dispense with the back disk, k, of the frame G, (shown in said patent,) and in place thereof make the back plate or bracket, F, constitute a part of the frame, to which are 35 secured the posts f, and in which are pivoted the arbors of the bell-striking mechanism; and instead of extending the actuating-wire E through a hole in the ear b, as in said patent, I attach it near the free end of the arm O, thus gaining more leverage and doing away with the friction caused by said wire rubbing against the sides of the hole in the ear b. Said ear b in this case is formed as 40 shown, and the upper inclined face thereof constitutes a stop for the arm O when depressed by the wire E. The arbor p of the spring for operating the train in this case is extended beyond the outer surface of the disk i, and is formed prismatic, as shown, to admit 45 of a key being applied to it to wind the spring

t, to increase its power in case it should be desirable to do so. In case the spring t should lose its power, by removing the bell from its bearing and loosening the set-screw of the 55 arm u and applying a key to the prismatic end of the arbor p it can be revolved to increase the tension of the spring t as may be required.

The back plate or bracket, F, is made square 60 or rectangular in shape, as represented, and is provided with screw-holes near its corners for securing it in position. It is also chambered in its back, as shown in Fig. 2, so that it bears only at its edges against the surface 65 to which it is or may be secured.

In some cases I apply to the frame and to the arm O a take-up spring, L, as shown, which operates to assist the spring t to return the arm O to the position shown in full lines 70 in Fig. 1, after it has been depressed into the position shown in dotted lines in said figure by the actuating-wire E.

The arm O is provided with a notch, y, in which the free end of the spring L bears, and 75 said notch holds the said end of the spring in the position in which it will act to the best advantage on the arm and retains it in position while the arm is being depressed.

In other respects the mechanism of this 80 alarm is the same as that represented and described in the patent hereinbefore referred to, it having arranged on the arbor p the gear o, revoluble thereon, the actuating-spring t, attached to the arbor and to one of the posts f 85 of the frame, the ratchet r, fixed to said arbor, the pawl q, pivoted to the gear o, and the spring t, secured thereto, and the arm u, fixed to said arbor, a connecting-rod, v, joining the outer end of said arm u to the arm O, as 90 shown. On the bell-knob being pulled out, the actuating-wire E, attached thereto, will depress the arm O into the position shown in dotted lines in Fig. 1 against the stop b. Consequently the arm u will turn the arbor p, 95 and the ratchet-wheel r will move under its pawl s, and the spring t will be wound on its arbor. As soon as the bell-knob is released from the hand that pulled it the spring t will turn its arbor p and ratchet r, and consequently the gear o will put in motion the lantern-pinion n, fixed on the hub of the scape- 100

wheel *g*, and the rest of the train, by which the bell-hammer will be vibrated and caused to strike the bell successively a number of times, or till the free end of the arm *O* brings 5 up against the escapement-arbor *h*.

From the above it will be seen that by my improvements I have reduced the number of parts of the mechanism, as shown and described in the patent referred to, and consequently have correspondingly reduced the cost of manufacture of the alarm, and by connecting the actuating-wire *E* near the free end of the arm *O* and arranging said wire outside of and away from the stop *b* have 10 done away with much friction, and have provided an alarm which is simplified in construction and more easily operated than that hereinbefore referred to; therefore,

Having described my invention, what I claim 20 in alarms for doors, &c., is—

1. The combination of the frame constructed as described and provided with the inclined stop, as shown, and having the bell-hammer-operative mechanism arranged therein, as 25 represented, said mechanism consisting of the arbor *p*, mainspring *t*, and ratchet *r*, fixed thereto, gear *o*, revoluble thereon, pawl *g*, and spring *t*, connected to said gear *o*, the lantern pinion, scape-wheel, and shaft, the pallets and 30 their shaft, with the arm *O*, pivoted in the

frame connected with the arbor *p* of the main-spring by the arm *u* and link *v*, as shown, and having the actuating-wire *E* applied to it near its free end, all substantially as described and represented.

35

2. The combination of the frame constructed as described and provided with the inclined stop, and having the bell-hammer-operative mechanism arranged therein, essentially as set forth and represented, with the arm *O*, 40 pivoted in the frame, connected, as shown, with the mainspring-arbor *p*, by the arm *u* and link *v*, and the take-up spring *L*, secured to the frame and applied to the notch *y* of the arm *O*, as represented, the actuating-wire being attached to the said arm near its free end, all as shown, and for the purpose set forth.

45

3. The back plate, *F*, constructed as shown, and provided with the inclined stop, in combination with a door-bell-alarm apparatus secured to said plate *F* and having the pivoted arm *O*, and the stop limiting the movement of the arm, as and for the purpose set forth.

50

In testimony whereof I affix my signature in presence of two witnesses.

NATHUM J. BUSBY.
